* cited by examiner

Primary Examiner — John R Yeh(74) *Attorney, Agent, or Firm* — Hankin Patent Law, APC; Kevin Schraven; Anooj Patel(57) **CLAIM**

The ornamental design for the multi-use mop, as shown and described.

DESCRIPTION

FIG. 1 is a top perspective view for a multi-use mop showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines depict portions of the multi-use mop that form no part of the claimed design.
